UNITED STATES PATENT OFFICE.

JAY R. DUNCAN, OF KEWANEE, ILLINOIS.

GAME-CARDS.

1,349,189.

Specification of Letters Patent. Patented Aug. 10, 1920.

Application filed May 21, 1919. Serial No. 298,590.

To all whom it may concern:

Be it known that I, JAY R. DUNCAN, a citizen of the United States, residing at Kewanee, in the county of Henry and State 5 of Illinois, have invented certain new and useful Improvements in Game-Cards, of which the following is a specification.

This invention relates to game cards and has as one of its objects to provide a deck 10 the cards of which possess such characteristics as will adapt the deck for use in the playing of relatively simple or more complicated games so that the deck may be made use of by children or those who desire to play a game requiring but little mental exercise or it may be used by players who prefer a game embracing more intricate possibilities in its playing and requiring considerable mental exercise.

20 Another object of the invention is to provide a game card deck comprising a relatively small number of cards possessing such characteristics that a maximum number of possible plays may be made in the playing of one of the games for which the deck is adapted.

Another object of the invention is to provide a deck each card of which possesses a plurality of suit values so that while in the 30 present embodiment of the invention there is a total of thirty-six cards comprising three sets of twelve cards each, the thirty-six cards in reality comprise six suits of twelve cards each.

35 A further object of the invention is to provide a deck each card of which will not only possess a plurality of suit values but also a numerical value so that usefulness of the deck is greatly enlarged.

40 In the accompanying drawings the several figures designated as 1 to 6 inclusive represent views of different cards selected from the deck for the purpose of illustrating the principle of the invention.

45 The deck of cards forming the subject matter of the present invention preferably comprises a total of thirty-six cards which in accordance with suit values of one character may be classified in three sets of twelve 50 cards each, and in accordance with suit values of another character may be classified into three sets of twelve cards each differing from the sets of the first classification.

The cards are designated by numerical 55 values in such manner that the cards comprising each set of either classification men-

tioned will have their numerical values running in sequence. Thus each of the thirty-six cards bears words or symbols indicative of its two different suit values, and a numeral indicative of its numerical value. The verbal, symbolical, and numerical value-indicating indicia may be of an arbitrary nature and therefore within the spirit of the present invention it is not absolutely essential that the particular indicia illustrated in the drawings and hereinafter referred to be employed, the drawings being merely illustrative of one embodiment of the invention.

In the present instance twelve of the cards will bear the word "Yanks", this word appearing at each end of each of the said twelve cards and being a name given by some to the men of the American Expeditionary Force. Four of these twelve cards are illustrated in Figs. 1, 2, 3 and 5 of the drawings in which figures the word is indicated by the numeral 1. Likewise in diametrically opposite corners each of these twelve cards is provided with the initial letter of the word as indicated by the numeral 2. Likewise another twelve of the cards have printed thereon the word "French" as indicated by the numeral 3, located at each end of each card and bearing reference, of course, to the French troops. The remaining twelve cards have printed thereon the word "English" as indicated by the numeral 4, this word appearing at each end of each of the twelve cards and, of course, bearing reference to the British troops. One of the "French" cards is shown in Fig. 4 of the drawings and one of the "English" cards is shown in Fig. 6 of the drawings, the former card and the remaining ones of the suit to which it belongs having printed in diametrically opposite corners the initial letter of the word "French", as indicated by the numeral 5. In a similar manner each of the "English" cards has printed in its diametrically opposite corners the initial letter of the word "English" as indicated by the numeral 6. Each of the twelve "Yanks" cards bears numerals indicating the numerical value of the card as indicated by the numeral 7, the numerals upon each card being arranged adjacent the word "Yanks" at the respective ends of the card and the said numerals upon each card being relatively inverted so that the cards may be read when viewed

from either end. At this point it is to be noted that likewise the words "Yanks", "French" and "English" upon each of the respective cards are relatively inverted for the same purpose. The cards shown in Figs. 1, 2, 3, and 5 of the drawings have respectively the numerical values 9, 10, 5 and 8. As before stated there are twelve of these "Yanks" cards and the cards comprising the "Yanks" suit will be consecutively numbered from 1 to 12. Each of the cards of this suit will furthermore have printed in its before mentioned diametrically opposite corners the numerals 8 corresponding to the numerals 7. In like manner the twelve cards comprising the "French" suit will be consecutively numbered from 1 to 12 and the twelve cards comprising the "English" suit will be consecutively numbered from 1 to 12. Thus viewed in this light the deck of thirty-six cards comprises three suits, namely the "Yanks", "French" and "English" suits and each suit comprises twelve cards and the cards of each suit are given numerical values ranging from 1 to 12.

Each card is additionally identified by a suit designation in a sense wholly independent of the suit designations comprising the words "Yanks," "French" and "English" above pointed out, and these latter suit designations are of three different characters so that by them the thirty-six cards are classified in three additional suits. Thus twelve of the cards belonging to what may be termed the "money" suit have printed thereon between the numerals 7 a distinguishing symbol, in this instance the dollar mark (\$), as indicated by the numeral 9; another twelve of the cards, considered as belonging to the "food" suit will be printed between the said numerals 7 with a symbol representative of some article of food, in the present instance the representation of a loaf of bread, as indicated by the numeral 10; and, the remaining twelve cards will have printed upon them between the said numerals 7 a symbol such for example as a representation of the Red Cross as indicated by the numeral 11 indicating that these cards belong to the "women" suit. The "women" suit will comprise four cards from the "Yanks" suit, four cards from the "French" suit, and four cards from the "English" suit and preferably the cards from the "Yanks" suit belonging also to the "money" suit will be those having the numerical values of 3, 6, 9 and 12; those from the "French" suit the numerical values of 1, 4, 7 and 10; and, those from the "English" suit the numerical values of 2, 5, 8 and 11. The cards of the "Yanks" suit belonging also to the "food" suit will preferably be the cards having the numerical values 1, 4, 7 and 10; those from the "French" suit belonging also to the "food" suit will have the numerical

values 2, 5, 8 and 11; and, those from the "English" suit common also to the "food" suit will have the numerical values 3, 6, 9 and 12. Likewise the cards from the "Yanks" suit common also to the "women" suit will have the numerical values 2, 5, 8 and 11; those from the "French" suit common also to the "women" suit will have the numerical values 3, 6, 9 and 12; and, those from the "English" suit common also to the "women" suit will have the numerical values 1, 4, 7 and 10. Thus as before stated the "money" suit will comprise twelve cards designated with numerical values ranging from 1 to 12 inclusive and comprising four cards of the "Yanks" suit, four cards of the "French" suit, and four cards of the "English" suit. This is likewise true of the cards comprising the "food" and "women" suits. The cards of the "money," "food," and "women" suits are designated by their respective symbols in their before mentioned diametrically opposite corners as indicated by the numeral 12. It will now be evident that the twelve cards comprising the "Yanks" suit will embrace four cards from the "money" suit, four cards from the "food" suit, and four cards from the "women" suit, the same being true of the cards of the "French" and "English" suits. In practice for example the cards of the "money" suit belonging also to the cards of the "Yanks" suit will have the numerical values of 3, 6, 9 and 12; the four cards of the "food" suit belonging also to the "Yanks" suit will have the numerical values of 1, 4, 7 and 10; and, the four cards of the "women" suit belonging also to the "Yanks" suit will have the numerical values of 2, 5, 8 and 11. Likewise the "food" suit will comprise the cards of the "Yanks" suit having the numerical values 1, 4, 7 and 10; the cards of the "French" suit having the numerical values 2, 5, 8 and 11, and, the cards of the "English" suit having the numerical values 3, 6, 9 and 12. Also the cards of the "women" suit will comprise the cards of the "Yanks" suit having the numerical values 2, 5, 8 and 11, the cards of the "French" suit having the numerical values 3, 6, 9 and 12; and the cards of the "English" suit having the numerical values 1, 4, 7 and 10.

From the foregoing it will be seen that each card has two suit values and a numerical value. As a result by the use of the cards embodying the invention there may be a diversity of plays which could not be had if each card did not possess the characteristics stated. Also it will be evident that while the deck comprises only thirty-six cards, there are in effect six suits of twelve cards each due to the fact that it is possible to play any one of the cards either one of two ways, it being intended in one play to

belong to one suit and in another play to belong to another suit. Of course, the suits represented by the words "Yanks," "French" and "English" may be disregarded and the 5 cards played in accordance with the suits represented by the symbols designated by the numerals 9, 10 and 11, and vice versa.

Before proceeding to a statement of the rules by which two different games may be 10 played by the use of the deck of cards hereinbefore described, it may be stated that each "5" card counts five points to the player holding it at the conclusion of the game; the greatest number of cards of the "money" 15 suit held at the end of the game counts ten points; and, each hand taken counts five points.

Disregarding the "money", "food" and "women" suits a simple game may be played 20 as follows by two, three or four people: In dealing, eight cards are dealt to each player and a reserve of four cards is also dealt to be used by the first player, who should be the one to the left of the dealer. One card 25 played face up on the table, by each player constitutes a hand. The deal passes to the left.

The first player picks up the reserve of four cards and his other eight cards and 30 from these twelve cards he discards four, leaving eight in his hand which is the same number as held by each of the other players. Ordinarily it is best to discard the four lowest cards and if a player has a large 35 number of cards of one suit it will usually be best to discard the cards of another or other suits. A player should not discard any of the cards having the numerical value of "5" but may discard cards of the "money" 40 suit if he so chooses. In commencing the game, the player to the left of the dealer plays from his hand, any selected one of his cards which is placed face up upon the table and usually it will be found best to play the 45 card having the highest numerical value. If for example the card led is the "12" of the "Yanks" suit, the other player must follow suit if possible, or if they cannot they must play a card of the "English" suit, 50 either of which will, of course, be lost to them since the highest card of the suit led is the winning card. The winner of the hand collects the cards won and places them face down upon the table. The game is 55 continued in this manner and if desired the players may play partners. As before stated, the player having the greatest number of "money" cards at the conclusion of the playing of the hand receives ten points, 60 but if there is a tie these points are not counted.

If desired, bidding may enter into the playing of the game and in proceeding in this manner the player at the left of the 65 dealer calls out his bid and the next player

or players will increase this bid if possible, each player having but one bid. The one bidding the highest picks up the four reserve cards and from them and the cards dealt to him discards four cards which he 70 does not care to hold and then proceeds to play first. If a player fails to make his bid a corresponding number of points is deducted from his previous score. Following the rules stated above, there may be a variation 75 in the manner of playing the game by disregarding the "Yanks", "French" and "English" suits and considering only the "money", "food" and "women" suits.

A more difficult and intricate game may 80 be played by the following rules: The cards are dealt in the manner heretofore stated and the players may bid also as before stated and in addition may make trump, the trump suit as usual having preference 85 over the other suits and the advantages of trump cards over other cards being those well-known. At this point it will be understood that due to the peculiarity of the cards comprising the deck it is possible, for a 90 player to make the uncommon play of following suit and at the same time play trump in another suit and win the hand. Thus if the "food" suit is trump and the first card played was the "12" "French" card then the 95 remaining players should follow suit although a player could play, for example, the card belonging both to the "French" and "food" suits and having the numerical value of eight and winning the hand because he has not only followed the suit led but at the same time has played trump. Of course, in playing both suits simultaneously the player of the first card must designate the suit to be followed. Thus if the first 100 card led should be the "7" "French" and "money" card and the player designates the suit as "French", then the succeeding players must follow suit if possible or they may play a card from the trump suit. In the 105 next hand played the card led might be the "12" "English" and "food" card and the suit might be designated as "food". In view of the arbitrary designation of the suits, a player holding for example two "12" 110 cards would be in possession of the best 115 card in any one of four suits.

It will be observed from the foregoing that the cards of the various suits bear ordinals or numerical values increasing by a 120 progression of three.

Having thus described the invention, what is claimed as new is:

1. A game card deck comprising a number of cards divisible into a plurality of sets 125 of suits, the suits of one set relating to such matter different from that to which the suits of another set relate, and each card being common to a suit of each of the sets.
2. A game card deck comprising a num- 130

ber of cards divisible into a plurality of sets of suits, the suits of one set relating to such matter different from that to which the suits of another set relate, each card being common to a suit of each of the sets, and each card bearing indicia indicative of a numerical value.

3. A game card deck comprising a number of cards bearing indicia indicative of suit values whereby the total number of cards may be divided into a plurality of related suits, each card bearing indicia indicative of another suit value unrelated to the first mentioned value of the respective card whereby the total number of cards may be divided into a plurality of suits related to one another and unrelated to the first mentioned suits.

4. A game card deck comprising a number of cards bearing indicia indicative of suit values whereby the total number of cards may be divided into a plurality of related suits, each card bearing indicia indicative of another suit value unrelated to the first mentioned value of the respective card whereby the total number of cards may be divided into a plurality of suits related to

one another and unrelated to the first mentioned suits, each card bearing indicia indicative of a numerical value.

30

5. In a game card deck, cards numbered to divide the deck into consecutively numbered sets, each card having plural suit indicia dividing the deck into as many suits as there are consecutively numbered sets.

35

6. In a game card deck, cards numbered to divide the deck into consecutively numbered sets, each card having plural suit indicia dividing the deck into as many suits as there are consecutively numbered sets, one suit indicia of each card of each set corresponding to one suit indicia of the card of next numerical value in another set.

40

7. In a game card deck, cards numbered to divide the deck into three consecutively numbered sets, each card having as many different suit indicia as there are consecutively numbered sets, one suit indicia of each card of each set corresponding to one suit indicia of the card of next numerical value in another set.

45

In testimony whereof I affix my signature.

JAY R. DUNCAN. [L.S.]
